(57) **CLAIM**

The ornamental design for a port hole hanger, as shown and described.

DESCRIPTION

FIG. 1 is a front, left, top perspective view of a port hole hanger in accordance with the present invention;

FIG. 2 is a rear, right, top perspective view thereof;

FIG. 3 is a top plan view thereof;

FIG. 4 is a bottom plan view thereof;

FIG. 5 is a right-side elevation view thereof; and,

FIG. 6 is a left-side elevation view thereof.

The broken lines represent portions of the structure that form no part of the claim.
